PAPER FOLDING MACHINE

Application filed September 2, 1930. Serial No. 479,156.

This invention relates to machines for folding sheets of paper for various purposes, my principal object being to provide a machine of this character which will fold a sheet of paper along its opposite side edges and will then deliver the folded sheet from the folding mechanism, all in a continuous operation.

A further object of the invention is to provide a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

20 Fig. 1 is a side view partly in section of my improved paper folding machine showing the parts in their normal or non-operative position.

25 Fig. 2 is a cross section substantially on the line 2—2 of Fig. 1, showing a sheet of paper in place to be folded.

Fig. 3 is a side view of the machine showing the parts as moved to a paper folding position.

30 Fig. 4 is a fragmentary cross section on the line 4—4 of Fig. 3 showing the paper as folded.

Fig. 5 is a cross section on the line 5—5 of Fig. 1.

35 Fig. 6 is a perspective view of a sheet of paper as folded by the machine.

Referring now more particularly to the characters of reference on the drawings, the numeral 1 denotes a pair of transversely spaced rails for supporting sheets of paper 2, said rails having side flanges along their outer edges to locate the sheets. Intermediate the ends of the rails a vertically movable stop 3 of suitable character is provided, which stop normally projects between the rails so that the stack of sheets 2 will be supported on the rails ahead of the stop, as shown in Fig. 1. At their rear ends these rails align with similarly spaced ledges 4 which are formed in connection with an intermediate

platform 5 which is on a lower level than the ledges and extends the full length of the same. Narrow undercut transversely extending grooves 6 are provided at the junction of the side edges of the platform with the inner edges of the ledges. Stops 7 project upwardly above the ledges at their rear ends, the space between these stops being greater than the distance between the bottoms of the grooves 6.

The rails, ledges, and platform are all arranged as a rigid unit and are supported by bars 8 or the like which extend beyond the rear end of the platform and are adapted to be secured to a rigid supporting means such as a table 9 or the like. The supporting bars are arranged so that the rails and ledges have a considerable downward slant from the outer ends of the rails toward the table, so that the sheets of paper will tend to slide off themselves from the rails onto the ledges and until they abut against the stops 7.

Depending from and fixed in connection with the platform centrally of its width are transversely spaced bracket plates 10, on the lower end of and between which is pivoted a bellcrank 11, having relatively long and short arms. The short arm projects in a substantially horizontal and forward direction and is connected to an operating mechanism which may be power or manually actuated. In the present instance this mechanism is shown as being a foot treadle 12, which is pivoted at one end in connection with the floor or other rigid part, and is connected at its other end to said short arm of the bellcrank by an upstanding link 13. The other and long arm of the bellcrank normally projects upwardly and rearwardly to a point rearwardly of the rear end of the platform 5, and is there connected to a slide 14. This slide engages slide guide grooves 15 which are formed between the platform and the plates 10; said grooves being disposed so that they have an upward and forward slant relative to the plane of the upper surface of the platform. The forward end of the slide carries an upstanding finger 16 which projects into a slot 17 extending from top to bottom of the platform and from the front end of the same

100

rearwardly a certain distance. This finger is arranged so that when the slide is in its rear-most position the finger is below the level of the top of the platform, as shown in Fig. 1.

5 When however the slide is moved forwardly to its limit of movement the finger is then above the platform and is ahead of the front end of the same, as well as a sheet of paper resting thereon, as shown in Fig. 3. A tension spring 18 acts to hold the bellcrank and associated parts in their normal positions above described.

10 Lugs 19 project upwardly from the platform at the forward ends of the ledges 4 to the sides of the same and support the rearwardly extending arms 20 which are pivoted thereon. These arms support a transversely extending shaft or bar 21 from which a block 22 depends and which on its lower end 15 carries a hinge pin 23 which extends lengthwise of the platform and is parallel thereto. Hinged on said pin are opposed plates 24 which extend substantially the full length of the ledges and which are normally but yieldably held at a downward and obtuse angle 20 relative to each other by springs 25. When in this position the opposed lower edges of the plates are spaced apart a distance somewhat less than the spacing between the inner 25 faces of the ledges 4, and also lie above the plane of the ledges somewhat, as shown in Fig. 2. Links 26 connect the short arm of the bellcrank 11 with the arms 20 intermediate their ends, so that said arms will be depressed when the bellcrank arm and the 30 treadle are likewise depressed.

35 In operation a sheet of paper from the stack is allowed to slide into position on the ledges and against the stops 7 by suitable manipulation of the releasable stop 3; the portion of the sheet between the ledges being maintained in suspended relation to the platform. As soon as the sheet is in this position the treadle 12 may be depressed. This causes the slide 14 to move upwardly so that the finger 16 is finally positioned ahead of the sheet.

40 At the same time the arms 20 and the folding unit associated therewith, and consisting essentially of the plates 24, are depressed.

45 Such depression causes the opposed lower edges of the plates to engage the paper for its full length inwardly of the ledges, and of course presses the major area of the same down onto the platform. This leaves the side edge portions of the sheet upstanding between the ledges. A further depression of the treadle and folding unit tends to flatten out the plates 24 against the resistance of the springs 25 which causes the lower side edges of said plates to enter the grooves 6. This movement forces the adjacent portions of the paper into the grooves 6 also, imparting the desired bends or folds to the sheet a short distance from their side edges, so that

50 longitudinally extending side flanges 2a are formed, as plainly shown in Fig. 6.

Upon the release of the treadle and the raising of the folding unit, the finger 16 is again moved toward the rear. In so doing it 55 engages the forward edge of the folded sheet and forces the same clear of the ledge grooves and to a position where it can be grasped and removed from the machine by hand. The stops 7 do not then interfere with such 60 movement of the sheet, since in its folded condition the sheet is narrower than the space between the stops. Upon the parts resuming their original normal positions the machine is ready to receive another sheet to be folded. 65

If desired a counter may be operated in connection with the folding and delivering of the individual sheets. This may be easily done by making the pivotal shaft 20a of one of the arms 20 rigid with said arm so as to 70 turn therewith. The operating ratchet lever 28 of the counter may then be connected to said shaft so as to be actuated by the rotation of the shaft by suitable linkage or connecting mechanism, as indicated generally at 75 29 in Fig. 1, so that with each lowering of the arms 20 and depression of the folding plates, the counter will be actuated.

80 From the foregoing description it will be readily seen that I have produced such a device as will substantially fulfill the objects of the invention, as set forth herein.

85 While this specification sets forth in detail the present and preferred construction of the device, still in practice such deviations from such detail may be resorted to as do not form a departure from the spirit of the invention, as defined by the appended claims.

90 Having thus described my invention what I claim as new and useful and desire to secure by Letters Patent is:

95 1. A paper folding machine including transversely spaced ledges forming supports for a sheet of paper along its side edges, a platform between and lower than the ledges, 100 oppositely facing grooves extending lengthwise of the ledges, and being formed under the ledges at the level of the platform, and means for engagement with the sheet between the ledges to press the same down onto the 105 platform, whereby the sheet is bent and the portions of the sheet originally resting on the ledges project upwardly; and to then force the sheet at the bends into the grooves whereby to cause said portions to be folded 110 onto the main body of the sheet.

115 2. A structure as in claim 1, with means mounted in connection with the folding means and arranged to function subsequent thereto, to slide the folded sheet clear of the 120 ledges and platform.

125 3. A structure as in claim 1, with a finger to engage one end of the folded sheet, and means connecting said finger to the folding means to cause the finger to move to a sheet 130

engaging position by the time the folding has been effected, and to then travel lengthwise of the sheet to deliver the same from the plane of the ledges and folding means.

- 5 4. A paper folding machine including transversely spaced ledges forming supports for a sheet of paper along its side edges, a platform between and lower than the ledges, oppositely facing grooves extending lengthwise of the ledges and being formed under the ledges at the level of the platform, a pair of plates normally above and extending lengthwise of the ledges, said plates being disposed at a downwardly diverging angle 10 relative to each other from their adjacent edges, means yieldably holding the plates in such angular relation, the space between the lower edges of the plates being less than the distance between the ledges, and means for depressing the plates to cause them to press the sheet down onto the platform and to cause the plates to be flattened out so that their lower edges will be projected into the grooves.
- 25 5. A paper folding machine including transversely spaced ledges forming supports for a sheet of paper along its side edges, a platform between and lower than the ledges, oppositely facing grooves extending lengthwise of the ledges and being formed under the ledges at the level of the platform, a pair of plates normally above and extending lengthwise of the ledges, said plates being disposed at a downwardly diverging angle 30 35 relative to each other from their adjacent edges, means yieldably holding the plates in such angular relation, the space between the lower edges of the plates being less than the distance between the ledges, supporting 40 means for the plates including substantially horizontal arms pivoted at one end in connection with and above the ledges, means applied to the arm to pull the same down to depress the plates against the sheet, and 45 spring means acting to hold the arms raised.

6. A structure as in claim 4, with a finger to engage one end of the sheet, supporting means for the finger, means between the plate depressing means and finger supporting 50 means to move the finger to one end of the sheet when the plates are depressed, and vice versa, and guide means for the finger supporting means to cause the finger to move to a level above that of the platform only as 55 said finger approaches said one end of the sheet.

7. A paper folding machine including a support for a sheet of paper to be folded, means for folding the sheet when in position 60 on the support, means to operate the folding means including a reciprocating lever whose movement in one direction effects a folding operation, and means provided with said lever for engagement with the sheet to withdraw the same from the support with the

movement of the lever in the opposite direction.

8. A paper folding machine including a support for a sheet of paper to be folded, means for folding the sheet when in position 70 on the support, means to operate the folding means including a reciprocating lever whose movement in one direction effects a folding operation, a slide under and movable lengthwise of the support, the latter having a longitudinal slot therethrough, a finger on one end of the slide, connecting means between the slide and lever to move the slide, with the movement of the lever in a folding direction, so that the finger is then beyond one 75 end of the folded sheet, and means supporting the slide to cause said finger to then project above the level of the sheet.

9. A paper folding machine including a support for a sheet of paper to be folded, 80 means for folding the sheet when in position on the support, means to operate the folding means including a reciprocating lever whose movement in one direction effects a folding operation, a finger to project above the sheet 85 at one end, and means between the lever and finger to place the latter in such position at the conclusion of a folding operation, and to cause the finger to engage and draw the sheet along the support with the movement of the 90 lever in the opposite direction.

10. A paper folding machine including a support for a sheet of paper to be folded, means for folding the sheet when in position 100 on the support, means to operate the folding means, a movable member to engage one end of the sheet, and means between said member and the folding means to move the member to a sheet engaging position at the conclusion of a folding operation and to 105 cause said member to withdraw the sheet from the support only subsequent to the conclusion of a folding operation.

In testimony whereof I affix my signature.
